METHOD OF DIE ROLLING

Filed Oct. 6, 1925

Patented Aug. 31, 1926.

UNITED STATES PATENT OFFICE.

PAUL L. COYLE, OF PITTSBURGH, PENNSYLVANIA, ASSIGNOR TO WITHEROW STEEL COMPANY, OF PITTSBURGH, PENNSYLVANIA, A CORPORATION OF PENNSYLVANIA.

METHOD OF DIE ROLLING.

Application filed October 6, 1925. Serial No. 60,757.

This invention relates to dia rolling, and particularly to a method whereby the useful life of a pair of die rolls may be multiplied many times with an expense which is very slight compared with the expense of a new set of rolls.

Die rolling is accomplished by the use of a pair of rolls having matrix portions cut therein and, particularly in those portions of the roll where a heavy reduction is effected, the rolled metal at the corner of the matrix portion and the periphery of the roll becomes badly pitted and worn. In addition to this, various other portions of the roll which come in contact with the hot metal are pitted or cracked and as a result the roll soon becomes unfit for further production. Generally speaking, the limiting factor on the mill run of any particular shape is the wear on the rolls, and after a certain length of time, even though regrinding while the rolls are in the mill in place is practiced as disclosed in the pending application of William P. Witherow, Serial No. 44,111, filed July 16, 1925, the rolls are no longer fit for the production of commercial articles and heretofore have been scrapped or else cut down to such diameter that the matrix portions have been entirely removed and the smooth rolls of smaller diameter thus provided are used in the production of smaller articles.

I provide for reducing the diameter of a used roll slightly and working out the matrix portion to substantially its original depth. For example, a roll for the production of a rear axle shaft for automobiles may have a matrix portion which in some places is nearly an inch deep. When a roll of this character has been worn out it is placed in a lathe and reduced in diameter from $\frac{1}{8}$ to $\frac{1}{16}$ inches and the matrix portions are recut to substantially their original depth.

It will be appreciated that during this process the matrix portions will be reduced somewhat in their length and I have found by actual experience that the reduction in diameter and corresponding reduction of the length of the matrix portions is offset in a large degree by an increased extrusion effect produced by the smaller roll. This being the case, a reduction of $\frac{1}{16}$ of an inch, or even of $\frac{3}{16}$ of an inch, in diameter, with the corresponding shortening of the matrix

portions of the roll, does not appreciably affect the length. In other words, a roll may be redressed once and sometimes twice without any attempt to increase the length of matrix portions to their original length and the rolls will nevertheless produce articles of desired dimensions. In practice rolls have been redressed as many as five times, but it is found that after the second redressing the matrix portions should be lengthened somewhat as the extrusion effect does not increase readily enough to compensate for the reduction in length of the matrix portions. Provision is therefore made in the original roll of a gate between successive article producing portions in the roll and this gate is shortened on successive redressings.

Very frequently it is found, especially with rolls made of such alloys as "adamite", that the desirable characteristics of the roll material are enhanced during the first run and that as a result a redressed roll stands up better on successive runs than does a new roll. This, of course, is of decided value for it tends to reduce the lost mill time.

In the accompanying drawings, illustrating one application of my invention:—

Figure 1 is a transverse section through a die roll indicating the manner of redressing in chain lines;

Figure 2 is a section on the line II—II of Figure 1, and

Figure 3 is a side elevation of a die axle blank produced by the roll shown in Figures 1 and 2.

In the illustrated embodiment of the invention there is shown one of a pair of die rolls adapted for the production of a rear axle shaft, such as shown in Figure 3. The roll is what is called a "two-impression" roll. That is to say, it produces two axles on a single revolution. Each of these "impressions" comprises a matrix portion 2 for the production of the short taper 2^a on the axle shaft; a portion 3 for the production of the so-called long taper 3^a; a portion 4 for the production of the stub portion 4^a, and a portion 5 for producing a gate between adjacent axles on a string of die rolled blanks. The roll is preferably provided with four grooves G as shown in Figure 2, each of these grooves being identical.

The roll, with its companion, is placed in the mill and a run is commenced. The

various grooves are used in succession until all of them are worn out. They may then be renewed one or more times by grinding or polishing the matrix portions in the mill as set out in my application above mentioned, but sooner or later all of the grooves will be worn to such an extent that the roll in its then condition is no longer capable of producing commercial axles.

10 The roll is removed from the mill and returned to the roll shop where it is placed between centers and turned down a small amount. In practice it is found that a reduction in diameter of $\frac{1}{8}$ or $\frac{1}{16}$ inches is sufficient. This reduction in diameter is indicated in Figure 1 in heavy chain line 6. It is next necessary to deepen the matrix portions a corresponding amount, and this may be done in any desired way. It is found in practice that the reduced diameter roll has an increased extrusion effect and as a result the various matrix portions need not be so long as they were on the original roll. It is found for the first, and possibly the second, redressing, that if all of the matrix portions are simply increased in depth an amount corresponding to the decrease in radius of the roll, satisfactory results will be obtained in rolling.

25 30 This is indicated by the heavy chain line 7 in Figure 1.

After one or two redressings the increased extrusion effect is not sufficient to produce articles of the desired length and the matrix portions are then increased somewhat in length by incroaching on the gate producing matrix. This results in a string of articles with a shorter gate in between, but since this metal goes to scrap the desired results are obtained.

40 The greatest wear on the rolls occurs at the corners C and, of course, these corners are completely removed by the redressing process. It is found in practice that in many cases the characteristics of the rolled metal have been materially improved by the first working so that a redressed roll will do considerably more work than a new roll. In addition to this, it is, of course, much easier to work out the old matrix portion to desired dimensions than it is to cut an entirely new roll. The old matrix portions serve as a guide for the cutting tools and with a little experience a competent roll maker can increase the length of the matrix portions slightly if it becomes necessary and put the roll in shape for again producing the desired articles without recourse to the extensive calculations and close supervision which are necessary in the original design of the roll. Generally speaking, the roll maker simply follows the old matrix portions and redresses the entire peripheral surface of the roll.

65 The drawings show a roll having semi-

circular matrix portions therein, but obviously the invention is applicable to other types of rolls. For example, in a roll having rectangular matrix portions the advantages of my invention may be obtained by dressing simply the periphery of the roll and the bottom of the matrix portions. There is usually provided a slight draft on the sides of such rectangular matrix portions and these will also be dressed. The invention is applicable to die rolls for the production of practically every article which may be made by that process. Therefore, while I have illustrated and described one embodiment of the invention, it will be understood that it is not thus limited since it may be otherwise embodied or practiced within the scope of the following claims.

I claim:

1. The method of die rolling, which includes reducing the diameter of a used roll having a matrix portion therein, deepening the matrix portion correspondingly, and utilizing the increased extrusion effect of the smaller roll thus produced to compensate for the shortened matrix and produce a die rolled article of substantially the same length as was produced by the original roll, substantially as described.

2. The method of die rolling, which includes reducing the diameter of a used roll having a matrix portion therein, working out the matrix portion to substantially its original depth, and utilizing the increased extrusion effect of the smaller roll thus produced to compensate for the shortened matrix and produce a die rolled article of substantially the same length as was produced by the original roll, substantially as described.

3. The method of die rolling, which includes reducing the diameter of a roll, and utilizing the increased extrusion effect of the smaller roll thus produced to secure die rolled articles of substantially the length produced by the original roll, substantially as described.

4. The method of die rolling, which includes reducing the diameter of a die roll having matrix portions therein, working out such matrix portions to produce matrix portions of substantially the same dimensions in cross section as the matrix portions of the original roll in cross section and shorter around the perimeter of the roll than the matrix portions of such original roll, and utilizing the increased extrusion effect of the smaller roll thus produced to compensate for the shortened matrix and produce a die rolled article of substantially the same length as was produced by the original roll, substantially as described.

5. The method of die rolling, which includes using a roll until it is substantially

worn out, then redressing the roll over substantially its entire peripheral surface, and utilizing the increased extrusion effect of the smaller roll thus produced to compensate for 5 the shortened matrix and produce a die rolled article of substantially the same length as was produced by the original roll, substantially as described.

6. The method of using a die roll having 10 matrix portions therein connected by a gating, which includes reducing the diameter of the roll after it has been used, deepening the matrix portions, and encroaching upon the gating to secure the desired length for 15 the matrix portions, substantially as described.

7. The method of die rolling, which in-

cludes forming matrix portions in a die roll for the production of corresponding article portions of desired length, using the roll for 20 a desired length of time, and then reducing the diameter of the roll and redressing the matrix portions, the redressed matrix portions being of shorter length than the original matrix portions in accordance with the 25 reduced diameter of the roll so as to utilize the increased extrusion effect of the reduced diameter roll and thus produce article portions of substantially the same length as those produced by the original matrix por- 30 tions.

In testimony whereof I have hereunto set my hand.

PAUL L. COYLE.

worn out, then redressing the roll over substantially its entire peripheral surface, and utilizing the increased extrusion effect of the smaller roll thus produced to compensate for 5 the shortened matrix and produce a die rolled article of substantially the same length as was produced by the original roll, substantially as described.

6. The method of using a die roll having 10 matrix portions therein connected by a gating, which includes reducing the diameter of the roll after it has been used, deepening the matrix portions, and encroaching upon the gating to secure the desired length for 15 the matrix portions, substantially as described.

7. The method of die rolling, which in-

cludes forming matrix portions in a die roll for the production of corresponding article portions of desired length, using the roll for 20 a desired length of time, and then reducing the diameter of the roll and redressing the matrix portions, the redressed matrix portions being of shorter length than the original matrix portions in accordance with the 25 reduced diameter of the roll so as to utilize the increased extrusion effect of the reduced diameter roll and thus produce article portions of substantially the same length as those produced by the original matrix por- 30 tions.

In testimony whereof I have hereunto set my hand.

PAUL L. COYLE.

DISCLAIMER.

1,597,955.—*Paul L. Coyle*, Pittsburgh, Pa. METHOD OF DIE ROLLING. Patent dated August 31, 1926. Disclaimer filed March 28, 1928, by the assignee, by mesne assignments, *The Colonial Trust Company*, trustee.

Hereby disclaims from claim 6 any method of using a die roll except where the matrix portions of the die roll are so proportioned relatively to one another that flash is produced along both sides of at least a part of the article during the die rolling operation.

[*Official Gazette April 10, 1928.*]
